MATERIAL HANDLING MACHINE

Frank O. Paulson, Ridgewood, N. J.

Application August 4, 1949, Serial No. 108,570

13 Claims.

(Cl. 61—63)

1

This invention relates to material handling machinery and more particularly to hydraulic levee building machinery for building levees, fills and stockpiling along waterways and rivers from solid material dredged from the river or lake bed.

It is common practice, where natural conditions permit such operations along waterways and rivers, to build levees, make land fills and build stockpiles of solid material by hydraulically dredging these materials from the bed beneath the waterway or river. The dredge sucks up the solid material with a quantity of water and pumps it to the desired location where it is deposited. This mixture of solid material and water is called the "fluid mixture" and the levee, fill or stockpile is called the "fill."

The fluid mixture varies in density and is approximately 10% to 15% solids and 85% to 90% water. The solids usually comprise sand, gravel, 20 clays, silt or a mixture thereof.

Various methods are currently used for handling the fluid mixture. One of these methods (1) is to carry the fluid mixture in a pipeline supported on a trestle. Shuttered openings called "bleeders" are located on the underside of the pipeline. The solid materials, being of greater density than the water, tend to "drag" along the bottom side of the pipeline and are readily discharged through the bleeders. When the fill level is built up under the pipeline to the desired elevation, the bleeders are closed with the shutters. Additional bleeder pipe sections are added to the end of the pipeline, thus extending the fill.

Another method (2) is to start the fill with the pipeline raised to the desired elevation so that all the fluid mixture is discharged from the end of the pipeline. When the fill reaches the desired elevation, the flow is stopped and additional pipe sections are added to extend the pipeline.

Both of the above-mentioned methods have undesirable features that delay operations and make unsatisfactory fill. If the trestle and bleeder method is used, the trestle becomes a major expense item because it is buried under the fill and cannot be removed. Moreover, the construction and placement of the trestle consumes considerable time which delays the dredging operation. These same objectionable features apply to the second method. Also, if the second method is used, the excess water is discharged from the end of the pipeline with considerable force. This usually scours and washes away retaining levees. Control of the placement of the fill is most difficult because of the kinetic energy

5 stored in this excess water. In the second method the fluid mixture is all discharged from one opening. The solid materials separate from the water and build up a mound of fill with a huge crater directly in front of the end of the pipe. Occasionally, the excess water breaks out of the crater in a solid stream, causing a rapid scouring and washing of the fill. If the retaining levees are damaged, the fill process becomes unmanageable and the flow must be stopped to reconstruct the levee so the fill will be shaped to the specified dimensions. Also, the crater makes the addition of pipe, for extending the pipeline along the fill, difficult because the 10 depth of the crater requires trestle or shoring under the pipe. Excess water is trapped in the crater which not only causes the deposited material to settle slowly but also delays the drying process of the deposited material.

Various types of spoons have been used at the end of the pipeline in an endeavor to reduce the dynamic flow of the fluid mixture and produce a more even distribution of the fill. Although this does somewhat improve the conditions as compared with the plain discharge, the control of the fluid mixture is still erratic and difficulty is experienced in keeping the end of the pipeline at the proper elevation. This is more readily appreciated when it is considered that a flow of twenty feet per second in a twenty-four inch pipeline will liberate energy at the rate of approximately 27,000 foot-pounds per second at the discharge point. This energy must be absorbed in the turbulent crater or in the fill. The natural tendency of this released energy is to scour and wash away the slopes of the fill.

It is the object of this invention to overcome the above-described objections by reducing the particle velocity of the fluid mixture without reducing its volume rate of flow.

40 The foregoing object is achieved by this invention which provides, in combination with a dredge discharge pipeline, a plurality of buckets of the type used on hydraulic impulse wheels, a means for supporting the buckets to receive the discharge from the pipeline and move them, and a brake for controlling the speed of the buckets whereby the particle velocity of the discharged fluid mixture is reduced without reducing the volume rate of flow. The nozzle of the pipeline is made angularly adjustable to control the direction of deposit of the fluid mixture over selected areas of the fill. Power from the wheel may be used to slowly advance the rig or machine along the levee as the construction work proceeds. A 45 telescopic joint in the pipeline, back of the nozzle,

3

permits this advance of the wheel over the fill during pumping operations.

The invention may be better understood by referring to the accompanying drawings in which:

Fig. 1 is an elevation view of an embodiment of this invention disclosing the relation of the discharge nozzle and the impulse buckets;

Fig. 2 is a section view of the nozzle control apparatus of Fig. 1;

Fig. 3 is a plan view of the apparatus of Fig. 1;

Fig. 4 is a view illustrating the flow conditions prevailing when the nozzle is in a position to one side of its central position and the peripheral velocity of the wheel is less than one-half the velocity of the fluid mixture as it leaves the nozzle; and

Fig. 5 illustrates the apparatus building a typical levee.

In Fig. 1, the pipeline 1 is a conventional discharge line coming from a hydraulic dredge customarily used for this class of work. This line is connected to a telescopic joint 2 comprising an inner section 3 and an outer section 4. The inner section is preferably of substantially the same diameter as the pipeline 1. A flexible seal 6 is provided to permit the outer section 4 to slide over inner section 3 without leakage. A plurality of guides 7 are attached to the outside and near the end of the inner section 3. A similar set of guides 7 are attached to the inside and near the end of the outer section 4. These guides center the two pipe sections and remove the weight from the seal 6. This flexible joint enables the levee building machine to move along the top of the completed work as the fill progresses. In practice, the length of this telescopic joint 2 is about fifty feet. The rear end is supported by the pipeline 1 which in turn is supported on top of the levee by conventional means, not shown. The outer section 4 is secured to the deck of the machine by clamps 8. The use of this joint is very important in order to realize the maximum economic advantage of this invention. Its use permits a steady deposit of fill over a fifty-foot length of levee without the loss of any time for trestle building or moving machinery.

A nozzle 9 is attached to the reduced discharge end of outer section 4 by means of a flexible joint 10, better shown in Figs. 3 and 4. Joint 10 is of conventional construction and permits lateral and vertical movement of nozzle 9, by means shown in Fig. 2. This directs the fluid mixture angularly from its central position to assist in controlling the deposit of the fluid mixture in different areas across the surface of the fill. The modus operandi of this nozzle adjustment will be described in more detail later in connection with the description of Figs. 2 and 4. The path of the fluid mixture shown in Fig. 1 is the normal path that would be taken if this invention were not used. It should be noted that the mixture would strike the fill at substantially the same particle velocity it had when it left nozzle 9. This invention eliminates the destructive condition due to this high particle velocity.

An impulse wheel 11 is mounted in line with the discharge end of the nozzle 9. This wheel is preferably of the type commonly known as a Pelton wheel and is usually used to develop power from relatively small, high velocity water jets. This wheel carries a plurality of buckets 12 about its periphery. These may be either of the Pelton or of the Doble type or they may be a modification thereof. Preferably, they are a modified

4

Doble bucket without the splitter commonly used to divide the water jet into two parts. They thus have a smooth concave inner surface throughout. For maintenance reasons, these buckets are mounted to individual spokes 13 by bolts 14. The rest of the wheel construction is conventional and obvious from the drawing and requires no specific detailed description. The spokes radiate from hubs 15, better shown in Fig. 3 which, in turn, are keyed to a shaft 16. Shaft 16 is supported by bearings 17 at the outer ends of a pair of trusses each comprising struts 18 and 19. Shaft 16 is secured against thrust motion by a pair of thrust collars 20. The trusses are joined with additional truss members 21 and 22 which are secured to the deck of the machine.

A brake shaft 23 is mounted in bearing blocks near the upper ends of the truss members 22 as shown in both Figs. 1 and 3. A brake drum 24 is secured to one end of this shaft and the sprocket 25 is secured to the opposite end. A similar sprocket 26 is secured to shaft 16 and a chain 27 connects these two shafts. A suitable brake mechanism 28 of conventional design engages brake drum 24 to apply any desired mechanical load to shaft 23. It will be evident that as impulse wheel 11 is driven by the impulses received by the discharging fluid mixture from nozzle 9, shaft 23 will be driven through sprockets 25, 26 and chain 27. It is equally evident that any other mechanical linkage may be employed in place of the chain and sprocket, for example, bevel gearing and connecting shaft. Also, in practice, it is preferred that this entire drive be enclosed in a suitable casing to exclude the solid matter of the fluid mixture. This is not shown for the sake of clarity but is quite conventional.

Referring now to both Figs. 1 and 2, it will be noted that nozzle 9 is supported in yoke 29. The yoke 29 is given a lateral movement by a hand wheel 30 and associated gear and screw mechanism to move nozzle 9 to either side of its central position shown in Fig. 3. This movement is limited in its travel so that the discharge must always be caught by some portion of the buckets 12 as illustrated by the fluid flow in Fig. 4. If the center of the stream is directed to the centers of the buckets, the reverse flow will divide in substantially equal parts on either side of the center line of the bucket and nozzle as in the usual practice with Pelton power wheels. It is a well known property of Pelton power wheels that the particle velocity of the return flow relative to the buckets is always approximately equal to the velocity of the inflow, also relative to the buckets. This, of course, neglects the effect of friction which disperses the return flow and slightly lowers its return velocity. The absolute velocity of the return flow is, therefore, approximately equal to the difference between the absolute velocity of the flow from the nozzle and twice the bucket velocity. It is evident from this that if the buckets are moving with a peripheral velocity of one-half that of the nozzle discharge, the absolute velocity of the reverse flow is zero and the fluid mixture will simply drop to the fill. In practice, the bucket velocity is controlled by the brake mechanism 28 so as to give any desired absolute return flow velocity to aid in depositing the fluid mixture over different areas of the fill. In any case, this invention makes it possible for the absolute particle velocity of the return flow to be very slow compared with the discharge velocity from the nozzle so that washing away of the deposited fill is substantially eliminated. The water

easily separates from the solid matter and flows off freely over a large area. Thus, it is seen that the principle of the Pelton impulse wheel is uniquely employed to solve a very troublesome problem of long standing in the hydraulic levee building art.

If the nozzle is moved laterally in one direction, as seen in Fig. 4, the return flow will no longer be equally divided but will leave the buckets in a direction opposite from the deflection of the nozzle. The use of buckets with a continuously smooth curve concave surface renders this control by the nozzle particularly effective. It is thus seen that the discharge can be controlled in its placement fore and aft by the brake mechanism and laterally by the lateral movement of the nozzle. Some vertical movement of the nozzle will also be provided for correcting changes in flow velocity. The mechanism for this is conventional with Pelton wheels but a preferred mechanism adapted to the practice of this invention is shown in Figs. 1 and 2. It comprises a clamp 37 secured around nozzle 9, the upper end of which is attached to a screw and hand wheel mechanism 38 installed in the top of the yoke 29. It is to be understood that by turning the hand wheel, nozzle 9 is raised or lowered as required.

As the fill progresses and the desired level is reached, the machine can be driven forward by power derived from the impulse wheel. This is obtained through a clutch and gear mechanism 31 of conventional design. This mechanism is equipped with a clutch controlled by clutch lever 32, a selective gear mechanism controlled by shift lever 33 and a variable speed drive under control of hand wheel 34. Power is taken from shaft 23 which passes through the housing of mechanism 31. Power is delivered by way of drive shaft 35 to the Caterpillar treads 36, 36. This Caterpillar drive and associated steering mechanism are the same as are customarily used with such drives and hence their details are not shown or described in further detail. When the flow and solid matter content remain approximately constant, the speed control 34 can be adjusted to cause the machine to slowly creep along at just the right speed to keep up with the fill. As the machine advances, the telescopic joint 2 extends so as to maintain a continuous flow. When this joint has reached its limit of extension, it is disconnected from pipeline 1 and additional sections of pipeline are inserted.

The levee illustrated in Fig. 5 is typical of the type of fill made by the machine of this invention. The machine is shown centered on the top of a fill which may have a width of twenty-four feet. Thus the lateral movement of the nozzle and the braking action jointly control the deposit of approximately twelve feet on either side. Of course, these dimensions are to be considered illustrative only and are in no sense restrictive of the levee dimensions that can be built by the machine of this invention.

From the foregoing description it will be evident that this invention has made a unique use of the Pelton impulse wheel principle quite different from its usual use as a power source. It is also seen that this machine provides means for absorbing substantially all the dynamic energy of the flow which is so destructive of the previously deposited fill and of retaining levees, thereby overcoming a major difficulty with hydraulically operated levee building machines. It disperses the flow of mixture over a wide area, permitting the solids to separate from the water and

the excess water to flow slowly and evenly over the sides of the fill without destructive washing. By regulating the speed of the machine the desired amount of the fill can be deposited irrespective of the condition of the terrain. The telescopic joint permits continuous advance of the machine while pumping operations are underway, thereby eliminating expensive stoppages while advancing the machine. This is an important economic feature. The flexible nozzle permits an even distribution of the material in the fill by controlling the direction of the flow to the buckets of the impulse wheel. The braking mechanism, which regulates the speed of the wheel, gives fore and aft control of the deposit so that the fill may be placed anywhere from several feet fore of the wheel to any location between the wheel and the rig of the machine. The machine and operator are protected from the return flow by a baffle plate 39 mounted as indicated in Fig. 1.

A variety of modifications can be made to many of the parts of this machine without departing from the inventive concept. For example, the buckets used need have no particularly critical shape. The ones illustrated are preferred because they provide excellent control over the reverse flow from the buckets to the fill. Instead of using a Caterpillar drive, the machine can be propelled by a conventional walking beam mechanism or any other suitable conventional propelling mechanism. To move the machine about when the pipeline is disconnected or when there is no flow, an auxiliary engine, not shown, is mounted on the rig and coupled mechanically to the gear mechanism 31. This auxiliary engine is also used in cases of slow flow insufficient to provide power to drive the machine and also provide the control necessary to manage the deposit of the fill. The brake may be of any type and may include an electric generator and resistive load as is sometimes used for braking purposes. The invention has been illustrated by showing the buckets mounted on a wheel. This is the preferred arrangement but it is obvious that the buckets could be mounted on a continuous chain traveling over two or more sprockets.

What is claimed is:

1. In a hydraulic levee building machine for constructing a levee from the fluid mixture discharged from a hydraulic dredge pump, the combination of a discharge nozzle including means for connection to the hydraulic dredge pump, an impulse wheel having a plurality of buckets mounted on the periphery thereof, said wheel being rotatably supported opposite said nozzle with the discharge direction of the nozzle substantially tangent to the circular path defined by the buckets, whereby the buckets receive the fluid mixture and cause rotation of the wheel, and a brake mechanically connected to said wheel for applying a mechanical load to said wheel to control its speed.
2. In a hydraulic levee building machine for constructing a levee from the fluid mixture discharged from a hydraulic dredge pump, the combination of a discharge nozzle including means for connection to the hydraulic dredge pump, a rotatable impulse wheel having a plurality of buckets mounted on the periphery thereof, a rig for supporting said nozzle and said wheel with the discharge direction of the nozzle substantially tangent to the circular path defined by the buckets, whereby the buckets receive the fluid mixture and cause rotation of said wheel, a propelling mechanism for propelling the rig, a mechanical

coupling means for coupling the wheel to the propelling mechanism whereby power from the wheel may be used to propel the rig as the fluid mixture is discharged, and a brake mechanically coupled to said wheel for applying a mechanical load to the wheel to absorb sufficient power to control the speed of the wheel.

3. A levee building machine for constructing a levee from the fluid mixture discharged from a hydraulic dredge pump, said machine comprising a discharge nozzle including means for connecting it to the pump, an impulse wheel with a plurality of buckets about the periphery thereof, means supporting said impulse wheel directly in line with said nozzle so as to receive the discharge of the fluid mixture against its buckets whereby the wheel is rotated, and a braking means connected to said wheel to apply a mechanical load to the wheel, whereby the particle velocity of the fluid mixture as it leaves the wheel may be reduced without lowering its volume rate of flow.

4. The combination of claim 1 wherein said nozzle is angularly adjustable, whereby the fluid mixture is caused to discharge against said wheel from different angular directions so that the mixture may be deposited over selected areas of the levee under construction.

5. The combination of claim 1 and a means for advancing the machine along the levee while the fluid mixture is being deposited.

6. The combination of claim 2 with means including a telescopic joint for connecting the nozzle to a pipeline whereby said rig may advance continuously while the fluid mixture is being delivered through the pipeline to the nozzle and impulse wheel.

7. The combination of claim 2 wherein said propelling mechanism comprises a Caterpillar tread.

8. The combination of claim 3 wherein the nozzle is angularly adjustable to cause the fluid mixture to discharge against said buckets from different angular directions whereby the mixture may be deposited over selected areas of the levee surface.

9. A levee building machine comprising a discharge nozzle for discharging a fluid mixture, means including a telescopic joint for connecting the nozzle to a pipeline carrying the fluid mixture

from a hydraulic dredging machine, an impulse wheel with a plurality of buckets about the periphery thereof, means including a rig for supporting said impulse wheel to receive the discharge of the fluid mixture from the nozzle and against said buckets whereby the wheel is rotated, a propelling mechanism for propelling the rig, a mechanical coupling means for coupling the wheel to the propelling mechanism whereby power from the wheel may be used to propel the rig, and a braking means adapted to apply an adjustable mechanical load to the wheel.

10. The combination of claim 2 wherein said mechanical coupling means includes a variable speed control for adjusting the speed of the propelling mechanism relative to the speed of the wheel.

11. The combination of claim 9 wherein said mechanical coupling means includes a variable speed control for adjusting the speed of the propelling mechanism relative to the speed of the wheel.

12. In a hydraulic material handling machine for handling a fluid mixture of liquid and solid particles, the combination of a plurality of movable buckets each having a concave surface, a discharge tube for delivering and discharging the fluid mixture, means supporting the buckets and the tube so that the discharged fluid mixture is received by the concave surfaces of the buckets whereby the buckets are moved, and means for applying a mechanical load to said buckets to control their velocity, whereby the absolute particle velocity of the fluid mixture is substantially reduced as it leaves the buckets.

13. The combination of claim 12 and a means for angularly adjusting the nozzle so that the fluid mixture is received by said buckets from different angular directions across their concave surfaces.
